PIANO LIGHT

Nathan George Horwitt, New York, N. Y.

Application June 19, 1934, Serial No. 731,256

13 Claims. (Cl. 240—4)

This invention relates to a lamp mounted on the key lid of a piano. The key lid and the lamp together result in lighting means which can be set to shed light simultaneously on the music and on the keyboard of the piano. The lamp, which is elongated, is set upon the key lid with its longitudinal axis horizontal and parallel to the front of the piano, said lamp extending along a substantial length of said lid. The lamp has an elongated cylindrical shade with a longitudinal slot therein extending substantially the full length of the shade. Means are provided in the lamp suitable for mounting lighting means throughout the length of the shade, preferably in the form of an elongated tubular electric light bulb having its terminals at the ends of the longitudinal axis of the bulb. The key lid is provided with a longitudinal slot so that the light shining through the slot of the shade can shine through the lid onto the keyboard. The slot in the shade is made wide enough, so that when the lid is lifted to open position, light will shine from this slot upon the music held in the music holder of the piano, and at the same time through the slot provided in the lid onto the key board. Movable means are provided to shut off the slot in the shade varying amounts. It is possible to shut off the latter slot so that no light shines on the music but only on the keyboard. When the key lid is closed and the slot in the shade closed, means are provided to lock the shade so that said latter slot cannot be exposed, thereby preventing anyone, such as a child, from tampering with the electric light bulb within. Switching means are provided, so that when the key lid is down the current is cut off automatically from the light bulb to prevent heating of the keyboard and other parts of the piano, as would happen with the lid closed, if the light were left on for a considerable period. Other switching means are provided so that, with the lid raised, the light is automatically turned on when the slot in the shade is exposed more than a predetermined amount and automatically cut off when said slot is closed.

In my preferred form the lamp consists of two cylindrical shades one mounted within the other and adapted to have relative rotation with each other. Each shade is provided with a substantially similar slot. When said slots are placed in register, light can be emitted from the lamp. As the slots are brought out of register, the light emitted is reduced accordingly, until they are completely out of register, closing the lamp completely.

Other objects and advantages will become apparent upon a further study of the description and drawings in which:

60 Fig. 1 is a partial front elevation of the piano

showing the lamp attached to the key lid which is in closed position.

Fig. 2 is an end elevation of the piano.

Fig. 3 is an end elevation taken similar to Fig. 2, except that the key lid is in open position and light rays are indicated as coming from the lamp in open position, a portion of the end wall of the piano being broken away to show the parts more clearly.

Fig. 4 is a partial section to an enlarged scale taken along the line 4—4 of Fig. 1 and shows the master switch.

Fig. 5 is a partial broken section to an enlarged scale taken along the line 5—5 of Fig. 2 with all parts of the piano omitted except a portion of the front lip of the key lid. The light bulb is omitted.

Fig. 6 is a section taken along the line 6—6 of Fig. 5, a complete section of the lamp being shown and a portion of the key lid.

Fig. 7 is a section, similar to Fig. 6, taken along the line 7—7 of Fig. 5, except that a light bulb is shown, and the lid and lamp are shown in the open position shown in Fig. 3, the lamp shades being in open position, and

Fig. 8 is a section taken along the line 8—8 of Fig. 5 a complete section through the lamp being shown and a portion of the key lid, the bulb being omitted to show the parts more clearly.

The key lid 9 of a piano 10 has attached to the front lip 11 of said lid a lamp denoted in its entirety by the numeral 12. The lamp is shown in Figs. 1 and 7 to have in it an electric light bulb 13. The light bulb is preferably an elongated slender cylindrical bulb having its terminals at the opposite ends of the cylinder.

The lamp is provided with two elongated hollow cylindrical shades 14 and 15, the inner shade being marked 14 and the outer shade being marked 15. The shades 14 and 15 fit at their ends over hubs 16 and 17 (Figs. 1 and 5). Hubs 16 and 17 are fixed to the front lip 11 of key lid 9.

In the preferred embodiment of the invention, outer shade 15 is free to rotate on hubs 16 and 17 and over shade 14 which latter is fixed to said hubs. It is within the scope of the invention, however, to fix outer shade 15 and have the inner shade rotate or to have both shades rotatable.

Inner shade 14 is provided with an elongated slot 18, best seen in Figs. 5, 6 and 7, while outer shade 15 is provided with a similar slot 19.

In Fig. 6, shades 14 and 15 are so turned that their slots 18 and 19 are completely out of register, in which case the interior of the lamp is completely closed off. Were electric light bulb 13 lit, with the shades in the relative position just noted, no light would be emitted from the lamp. However, as will be explained hereinafter, when the lamp is thus closed, the light is automatically turned off. As slots 18 and 19 are set

in register, light can come from the lamp, the amount of light varying in accordance with the overlap of the slots.

Inner shade 14 is shorter than outer shade 15, the right hand (Fig. 5) overhanging portion of shade 15, being loosely mounted directly on hub 17, while the overhanging portion at hub 16 has mounted within it a ratchet ring 20 which fits loosely on said latter hub. A pawl 21 is pivotally mounted substantially at the junction of hub 16 and lip 11, a space being hollowed out (not shown) for the pawl. The heel of pawl 21 extends to the left and toward the middle of the thickness of lip 11, entering a hole 22 provided in said lip. Slidably mounted in said hole is a plunger 23. In hole 22, between the heel of pawl 21 and plunger 23 is provided a compression spring 24. Above the heel of the pawl is slidably mounted plunger 25, and between the top of plunger 25 and the top of hole 22 is a compression spring 26. When key lid 9 is closed, plunger 23 contacts with the top of front lip 27 of the piano, said lip being shown in section in Fig. 4. This forces plunger 23 up into hole 22 which is the position shown for it in Fig. 5, the lid in said latter figure being shown, as will be remembered, in closed position. When plunger 23 is pushed up into hole 22, it forces spring 24 up against the heel of pawl 21, causing its toe to engage the teeth of ratchet ring 20. This prevents outer shade 15 from being rotated towards its open position, clockwise rotation in Fig. 6. A lug 28 on ratchet ring 20 prevents shade 15 from being rotated counterclockwise, Fig. 6, beyond its closed position, by the engagement of said lug with the top of pawl 21.

When key lid 9 is lifted to open position, as in Figs. 3 and 7, spring 26, acting through plunger 25, forces down heel of pawl 21, disengaging said pawl from the teeth of ratchet ring 20, thereby releasing shade 15 for clockwise rotation to open position. At the same time, under the influence of spring 24, plunger 23 is caused to project beyond the edge of lip 11. It is thus seen that when key lid 9 is closed, and shades 14 and 15 have been moved to closed position, they cannot be moved to open position. By locking said lid in closed position, tampering with the lamp is effectively prevented.

Switching mechanism is provided, Figs. 5 and 8, which automatically sends current through light bulb 13, when shade 15 is moved to open position and which automatically shuts off the current when said shade is moved to closed position.

Hub 17 is hollowed out to hold a switch 29, which is of the well known type, that snaps off the current when switch lever 30 is in the position shown in Fig. 8 and snaps it on when said lever is tilted to the reverse position. A partial tilting of said lever in either direction causes it automatically to snap over the rest of the way. A forked lever 31 is pivotally mounted upon hub 17 in a space provided therein, the fork of said latter lever engaging switch lever 30. Shade 15 is provided with an inwardly projecting lug 32 in line with lever 31, so that when said shade is moved to closed position, clockwise motion as viewed in Fig. 8, said lug will engage the right hand end of lever 31. In Fig. 8, lug 32 is shown in its extreme position, with shade 15 completely closed, said lug in reaching this position having already given lever 31 a partial clockwise rotation which caused fork leg 33 to throw over switch lever 30 into the position shown. When shade 15

is moved to open position, counter-clockwise motion, Fig. 8, lug 34 contacts with the left hand end of lever 31 causing fork leg 35 to throw over switch lever 30 from the position shown, opening the circuit to electric bulb 13, said bulb being set between spring contacts 36, Fig. 5, the bulb itself not being shown in this figure. Continued rotation of shade 15 in a counter-clockwise direction is possible after lug 34 acting through lever 31 and fork leg 35 has caused switch lever 30 to be thrown into position opposite to that shown, that is tilted toward the right in Fig. 8, because lever 31 can have further counter-clockwise rotation as lug 34 continues to press against it. Lever 31 is rotated by shade 15 through lug 34, until the latter entirely clears the left hand end of lever 31. When shade 15 is moved again to closed position by rotating it clockwise, lug 34 clears the left hand end of lever 31, said lever having remained clear from the previous opening of shade 15. Said clockwise rotation causes lug 32 to engage the right hand end of lever 31 before said shade has reached its closed position. In order that lug 34 will pass the lower end of switch 29, said switch is tilted back (not shown) with its lower end below the plane of the paper in Fig. 8, just enough so that when shade 15 is moved to open position, lug 34 will come in front of the lower end of switch 29. No wiring is shown from switch 29 to spring contacts 36, it being within the knowledge of skilled persons to hollow out portions of lip 11 and hubs 16 and 17 for suitable wires to run through. Similarly wires are brought to switch 29, through lid 9, the wires leading into said lid from the outside through tubular pivot 37 shown in Fig. 4. Before passing through pivot 37, the wires from the power supply are led to master switch 38, located in wood block 39, at the left end of keyboard 40, Figs. 1 and 4. Switch 38 is provided so that when the key lid 9 is closed, the current supply is automatically cut off from switch 29, so that the electric light bulb cannot remain lit when the lid is closed and thus subject the piano to undue and prolonged heat. Switch 38 has a plunger 41 which is normally spring held projecting toward the right as seen in Fig. 4. When the plunger 41 is free to project toward the right, the current is broken through switch 38. When lid 9 is rotated to open position, its heel 42 contacts with plunger 41, pushing it in and thus closing the circuit through switch 38.

It is to be noted in Figs. 6 and 7 that a slot 43 is provided in lip 11 of lid 9. Shades 14 and 15 are partially sunk into slot 43, that is they are set to extend inward from the front plane of lip 11. This reduces the amount the lamp projects from the front of the piano when the lid is closed, and with the lid raised, it allows, with certain types of grand pianos, the hinged top of the piano to be closed without coming against the top of the lamp. Said slot is substantially of the same length as slot 18 and comes opposite about one half the width of said latter slot. When shade 15 is in open position and the lid raised, Figs. 3 and 7, light from the electric light bulb 13 will pass through slots 18, 19 and 43 and fall upon keyboard 40. At the same time light will pass through the portions of slots 18 and 19 beyond lip 11 and fall upon any music that might be held in music holder 44.

Shade 15 can be set to any amount of closure, so as to control the light emitted. If partly closed only the keyboard is lit and the music is in darkness.

Wires 45 lead from spring contacts 36 through switches 29 and 38 to the electrical supply. As stated hereinbefore the details of the wiring are not shown.

5 Outer shade 15 is in effect a shutter for closing off slot 19 of inner shade 14.

I claim:—

1. A piano light comprising a pair of elongated cylindrical shades, one loosely mounted within 10 the other for relative rotation of the shades with respect to each other, and a pair of hubs for mounting said shades on the key lid of a piano with the longitudinal axes of the shades substantially parallel to the front of the piano, a hub 15 being located at each end of the shades one of said shades being fixed against rotation with respect to the hubs and the other free to rotate with respect thereto, a portion of each hub extending within the shades and acting as a bearing 20 for the free shade, said shades being each provided with a longitudinal slot, the rotation of the free shade bringing the slots into and out of register.

2. In combination, a key lid mounted on the 25 front of a piano, said lid when down closing off the keys of the piano, and a lamp comprising a pair of elongated tubular shades, one loosely mounted within the other for relative rotation of the shades with respect to each other, means 30 for mounting a source of electric light in said shades, means for mounting the shades on the key lid of a piano with their longitudinal axes substantially parallel to the front of the piano, said shades being of a length to extend along a substantial portion of the keyboard, said shades 35 being open for a substantial portion of their lengths, the rotation of said shades relatively to each other bringing the open portions of the shades into and out of register with each other 40 for controlling the emission of light through the shades, said shades being so located with respect to the music holder of the piano when the lid is raised, that light shining through the shades will fall upon the music, said lid being slotted 45 opposite said shades and with respect to the keyboard, that light shining through the shades will pass through the lid and fall upon the key-board when the lid is in raised position.

3. In combination, a key lid movably mounted 50 on the front of a piano, said lid when down closing off the keyboard of the piano, and a lamp comprising an elongated tubular shade mounted on the lid with the longitudinal axis of the shade substantially parallel to the front of the piano, 55 said shade having a longitudinal slot extending a substantial portion of the length of the shade, movable means for shutting off and exposing said slot, means for mounting a source of electric light in said shade, said shade being so located 60 with respect to the music holder of the piano when the lid is raised, that light shining through the slot of the shade will fall upon the music, said lid being slotted opposite the slot of the shade, and with respect to the keyboard, that light shining through slot of the shade will pass 65 through the lid and fall upon the keyboard when the lid is in raised position.

4. In combination, a key lid movably mounted 70 on the front of a piano, said lid when closed shutting off the keyboard of the piano, a lamp mounted on the lid, means for connecting an electric light bulb mounted in the lamp to an electric supply, said lamp, when the lid is opened being located to throw light simultaneously on 75 music held in the music holder of the piano and

on the keyboard, and switch means associated with said connecting means actuated by closing the lid to effect the cutting off of the electric supply.

5. In combination, a key lid movably mounted 5 on the front of a piano, said lid when closed, shutting off the keyboard of the piano, a fixed block located at one end of the keyboard opposite an end of said lid, a lamp mounted on the lid, means for connecting an electric light bulb 10 mounted in the lamp to an electric supply, said lamp, when the lid is opened, being located to throw light simultaneously on music held in the music holder of the piano and on the keyboard, and switch means associated with said connecting 15 means actuated by the coming together and separation of said block and said end of the lid as said lid is opened and closed to complete the circuit from the electric supply to said connecting means when the lid is opened and to break 20 said circuit when the lid is closed.

6. In combination, a key lid movably mounted 25 on the front of a piano, said lid when closed shutting off the keyboard of the piano, a lamp comprising an elongated tubular shade mounted on 30 the lid with the longitudinal axis of the shade substantially parallel to the front of the piano, said shade having a longitudinal slot, movable means for shutting off and exposing said slot, means for mounting a source of electric light in 35 the shade, said slot, when the lid is opened, being located to permit the light passing through it to fall simultaneously on music held in the music holder of the piano and on the key board and locking mechanism associated with the movable 40 means for locking same against motion to expose the slot, the locking action of said mechanism being effected when the lid is set in closed position.

7. A combination as claimed in claim 6, in 45 which the locking mechanism is mounted on the lid with a portion projecting therefrom, said portion contacting with a stationary portion of the piano when the lid is closed, effecting thereby the locking action of said mechanism.

8. A combination as claimed in claim 2, in 50 which one of the shades is fixed against rotation relatively to the lid, the other being rotatable relatively to the lid, said combination having in addition locking mechanism mounted on the lid associated with said rotatable shade, said mechanism having a portion movable with respect to the lid, said portion contacting with a stationary portion of the piano when the lid is closed, causing thereby the locking mechanism to prevent the 55 rotation of the rotatable shade in a direction to move its slot out of register with the slot of the fixed shade.

9. A piano light comprising a pair of elongated tubular shades, one loosely mounted within the other for relative rotation of the shades with respect to each other, means for mounting said shades on the key lid of a piano with their longitudinal axes substantially parallel to the front of the piano, one of said shades being fixed against 60 rotation relatively to said lid, means for connecting an electric light bulb mounted in the lamp to an electric supply, said shades being each provided with a longitudinal slot, the rotation of the movable shade relative to the fixed one bringing 65 the slot of the movable shade into and out of register with the slot of the fixed one, and a switch device, associated with the movable shade, actuated by same to cut off the electric supply to the light bulb when its slot is out of register by more 70 75

than a predetermined amount with the slot of the fixed shade.

10. In combination a key lid mounted on the front of a piano, a lamp comprising a pair of elongated shades one loosely mounted within the other, means for mounting said shades on the key lid with their longitudinal axes substantially parallel to the front of the piano, said shades being of a length to extend along a substantial portion of the keyboard, one of said shades being fixed against rotation relatively to said lid when mounted thereon, while the other one is rotatable about its longitudinal axis, the fixed shade being provided with a longitudinal opening, the rotation of the rotatable shade shutting off and exposing said opening, the opening of the fixed shade being located with respect to the music holder of the piano and the keyboard when the lamp is mounted on the lid and the latter is in raised position that light shining through its opening will fall upon the music and the keyboard.

11. In combination, a key lid mounted on the front of a piano, said lid when shut closing off the 25 keys of the piano, and a lamp comprising an elongated tubular shade mounted on the lid with its longitudinal axis substantially parallel to the front of the piano, said shade being open for a substantial portion of its length, means for shutting off and exposing said open portion, said lid having a slot therein in register with the open portion of the shade, said shade being partially sunk in said slot, said slot being located with respect to the keyboard when the lid is raised, that light shining through it falls upon the keyboard.

- 30 35 12. In combination, a key lid rotatably mounted on the front of the piano, said lid having a front

lip which stands in a substantially vertical position when the lid is down and closing off the keyboard, said lip extending in a substantially horizontal position when the lid is raised, and a lamp comprising an elongated shade mounted on said lip with the longitudinal axis of the shade substantially parallel to the front of the lip, said shade being open for a substantial portion of its length, means for shutting off and exposing said open portion, said lip having a slot therein in register with the open portion of the shade.

13. In combination, a key lid mounted on the front of a piano for closing off the keys of the piano, a lamp mounted on the lid, said lamp comprising a pair of elongated tubular shades one 15 loosely mounted within the other, means for mounting said shades on the key lid with their longitudinal axes substantially horizontal and parallel to the front of the piano, one of said shades being fixed against rotation relatively to 20 said lid while the other one is rotatable about its longitudinal axis, and means for mounting a source of light inside the shades and for transmitting electric current thereto, said shades being each provided with an opening, said openings being brought into and out of register in accordance with the motion of the rotatable shade, said lid having an opening therein in register with the opening of the fixed shade, the opening in the fixed shade and the opening in the lid being so 30 located when the lid is raised, that with the openings in the shades in register, light will shine through the shade and lid openings upon the keyboard and through the shade openings upon the music.

NATHAN GEORGE HORWITT.
